UNITED STATES PATENT OFFICE.

THOMAS B. CAMPBELL, OF NEW YORK, N. Y.

DESIGN FOR A GLASS VESSEL OR SIMILAR ARTICLE.

47,151.

Specification for Design.

Patented Mar. 30, 1915.

Application filed May 27, 1914. Serial No. 841,391. Term of patent 7 years.

To all whom it may concern:

Be it known that I, THOMAS B. CAMPBELL, a citizen of the United States, residing in the city of New York, borough of Brooklyn, in the county of Kings and State of New York, have invented a new, original, and ornamental Design for a Glass Vessel or Similar Article, of which the following is a specification, reference being had to the accompanying drawings, forming part thereof.

Figure 1 is a side elevation of a cut glass

vessel showing my new design applied thereto; and Fig. 2 is an inverted plan view of the same.

I claim:

The ornamental design for a glass vessel or similar article, as shown.

THOMAS B. CAMPBELL.
